UNITED STATES PATENT OFFICE.

WILLIAM W. HENDERSON, OF WASHINGTON, DISTRICT OF COLUMBIA,
ASSIGNOR TO INDUSTRIAL TRANSPORTATION COMPANY, A CORPO-
RATION OF THE DISTRICT OF COLUMBIA.

EXPLOSIVE-ENGINE.

No. 826,101.

Specification of Letters Patent.

Patented July 17, 1906.

Application filed October 19, 1904. Serial No. 229,120.

To all whom it may concern:

Be it known that I, WILLIAM W. HENDERSON, a citizen of the United States, residing at Washington, District of Columbia, have 5 invented certain new and useful Improvements in Explosive-Engines, of which the following is a specification, reference being had therein to the accompanying drawings.

This invention relates to improvements in 10 explosive-engines; and it is embodied in the construction and arrangement of parts presently to be described, and defined in the claims.

The invention relates more particularly to 15 that class of explosive-engines known as "compression-engines"—that is, wherein the charge is compressed—and, further, that class of engines wherein a rotary piston is employed as distinguished from a reciprocating piston.

The present invention is designed largely 20 and more particularly for the economic utilization of the explosive force of the gas in connection with a rotary piston of an engine or motor; and one of the principal aims of 25 the invention is the provision of a structure embodying general mechanical simplicity with a minimum number of parts, an engine which will be effective in the utilization of 30 substantially the major portion of the effect of the explosive charge, and, finally, an engine having provision for adjusting or varying the amount of explosive material constituting the charge.

In the accompanying drawings I have 35 shown an embodiment of the invention showing substantially the mechanical features, construction, and relative position of the parts. However, it is to be understood that 40 the positioning and proportioning of the device, as shown, may be changed in actual construction to properly time the various movements of the different parts and also that various modifications and changes can 45 be made without departing from the invention.

In the drawings, Figure 1 is a longitudinal section, showing parts in elevation, of an engine embodying the invention. Fig. 2 is a 50 transverse longitudinal section showing parts in elevation. Fig. 3 is a detail elevation of a cam. Fig. 4 is a detail view of one of the links or connecting-rods, and Figs. 5, 6, 7, 8,

9, 10, 11, 12, and 13 are detail views or the packings.

In the drawings, A designates the cylinder or casing, having a cylindrical extension B at a point on its edge. The interior of the casing A is circular or cylindrical, and through the sides of the casing passes the driven shaft 60 C, on which is mounted the rotating piston D. This piston is of peculiar construction, having a straight impact-face d extending radially from a point inward toward the center, from which point the piston is formed into a 65 true circle for a distance substantially equal to one-quarter of the circumference of such circle, while from the point d', being the point where the circular portion ceases, the edge of the piston is curved outward to and 70 terminates gradually at the outer or true circumference of the piston, as shown in Fig. 2. The construction of the piston results in the formation of a chamber D' between the edge of the piston and the casing, which chamber 75 tapers gradually at one end.

E designates a reciprocating abutment working in a radial recess or chamber e, formed in a projection of the casing. This abutment is conveniently composed of two 80 members e' e'', in each of which is formed a kerf or groove e''' near one edge, the same leading in from one end and terminating at a point adjacent to the opposite end, as shown in Fig. 5. These plates are placed side by 85 side with their grooved portions arranged in opposite relation, as shown in Fig. 6, and the extreme width of the plates is such as to cause them to fit closely in the chamber e, the kerfs or grooves in the plates being such 90 as to permit the narrow portions thereof bending inward slightly, thereby forming a spring, whose normal tendency is outward against the sides of the containing-chamber and the adjacent sides of the cylinder. By 95 this means a close joint is formed, preventing leakage. The abutment is backed up conveniently by a coil-spring E', adjustably held by a screw-plug E'' at the end of the chamber e, so that in action the movement of 100 the piston D will gradually force the abutment back, and the spring E' will immediately force the abutment inward after the same has passed the impact-shoulder d of the piston. It is to be understood in this respect that any other convenient form of 105

abutment can be employed in connection with this engine.

Heretofore it has been a difficult problem to prevent the escape of gases around the edges and sides of a rotating piston, and I have endeavored to overcome this defect in the following manner: In the side walls of the cylinder at points intermediate the center and edges are formed channels or grooves f , which have inwardly-inclined inner side walls and oppositely or outwardly inclined outer side walls. These channels are continuous and concentric with the axis of the driven shaft, and in the channels are placed the packing-rings F , conveniently formed of metal and of a shape in cross-section substantially that of the grooves f , but of a diameter slightly less than that of the grooves, so that the same will be permitted movement in a direction into and out of the grooves. These rings are conveniently split diagonally, as shown in Fig. 9, and their natural warp or set is such as to make their diameter greater than the diameter of the grooves f , so that when the same are forced into the grooves their natural tendency will be to expand and ride up or inward on the outer inclined walls of the grooves f , and thereby to bear against the sides of the piston D with a close yielding fit.

The packing-rings are placed close to the concentric cut-away portion of the piston, as shown in dotted lines, Fig. 2, and the impact-shoulder d is also provided with a packing, so as to practically preclude the escape of the gases past the sides of the outer portion of the piston. The packing for the impact-shoulder consists conveniently of three plates $g' g^2$, the former being imperforate except for a central opening. The plate g' is formed with oppositely-arranged grooves or kerfs spaced an equal distance apart and extending longitudinally, while the plate g^2 is kerfed or grooved transversely, the grooves and kerfs extending in from opposite edges. These three plates are brought up and held close against the impact-shoulder by a set-screw or bolt G , taking into the piston. The size of the plates $g' g^2$ is such that when crowded into position they will yield, and their natural tendency will be to bind with a close fit against the sides and ends of the cylinder and piston, thus forming in conjunction with the packing-rings a zone or field which is substantially closed against the escape of gases when the abutment is in position.

The extension B of the casing has a cylindrical bore tapering, as at b , at its upper end, which is substantially conical and communicates with the interior of the casing or cylinder. Within this cylindrical portion of the extension is a piston-head H , having suitable packing-rings and a hollow central portion, which center is closed normally by a valve h ,

having a stem h' , passing downward through the stem H' of the piston H , and this valve h is normally held closed by a relatively weak spring h^2 , sleeved about its lower end, located in a recess in the lower end of the stem H' and resting with its lower end against an adjustable nut h^3 on the end of the stem H . J and J' designate feeds for the charge leading into the bottom of the cylindrical extension B , the point of entry being suitably provided with check-valves j .

The manner of feeding the charge into the compression-cylinder B , I have not shown; but any well-known method or construction may be employed.

To compress the charge of explosive material which has been admitted to the compression-cylinder, I employ conveniently two cams $K K'$, fixedly secured, respectively, on the shaft C , and between these cams and the bearing-boxes for the shaft I place the links or rods L , which have elongated slots in their upper ends through which the shaft C passes. These slots are sufficient in length to permit of a full reciprocation of the rods or links L , which reciprocation is secured by the movement of the cams $K K'$, the respective rods carrying suitable projections k , carrying rolls at their ends entering into the grooves of the cams $K K'$. By this means the movement of the rods as to time and extent is governed and determined by the character and shape of the cam, which may be varied according to the demands or purposes to which the machine is to be employed. The rods L are guided through suitable guides l on the compression-cylinder B and carry at their lower ends a cross-head M , which in turn carries fixedly the piston H , so that upon the movement of the rods or links L a corresponding movement will be imparted to the piston H .

To vary the degree or to predetermine the point or time when the valve h will be opened so that the period of ingress of the combustible material to the combustion-chamber may be lengthened or shortened, I provide conveniently a reciprocating bar N , having a lateral projection n , the end of which extends directly under the end of the valve-stem h' , as shown in Fig. 2. This rod N is formed at its upper end with a pivoted section n' , carrying a head n^2 , below which is sleeved a resistance-spring n^3 . The spring and the upper end of the rod are incased in a tube O , having a shouldered lower end against which the lower end of the spring rests, and also having an eye in its upper end by which it is attached to the rocking lever P , pivoted on any suitable support and having a handle portion p . This lever P is designed to have a portion engage with a suitable toothed rack p^2 in any convenient manner, so that the lever may be held in its adjusted position.

As above stated, the space within the cylinder when used as an explosive-chamber is

packed against the escape of the gases. Evidently, however, when the gases are contained wholly in the compression-cylinder during the interval when the true outer surface of the piston is over the port leading from the compression-cylinder to the cylinder proper manifestly the gas would escape around the sides of the piston D through the exhaust A². To avoid this, I have provided 5 a ring packing R, first fashioning the walls of the port or opening at the upper end of the compression-cylinder so that it will have a double inclined wall, as shown in Figs. 12 and 13. I then provide a packing-ring having 10 its outer face formed to correspond in shape with the shape of the double inclined walls of the port as to angle, but of a width slightly greater than the walls of the port. This ring R is normally expanded, and owing to its inclined outer edge fitting on the inclined edge of the port the normal tendency would be to cause the same to raise or project inwardly into the cylinder. As soon, however, as the piston D is moved from the position shown in 15 Fig. 2 to an opposite position the ring R will be forced down, and its normal spring tendency will cause it to hug tightly against the edge of the piston D. The spring quality of the packing R is such as to result in its normal 20 positioning, and I have found that a ring of cast-iron will subserve the purposes and effectually retain its resiliency notwithstanding the heat of the chamber caused by the explosions.

25 In operation the parts are to be adjusted, positioned, and fashioned so that when the charge has been ignited in the chamber by any suitable means, such as an electric igniter, the points of which are shown in Fig. 2 at S, the piston D is driven forcibly around and the compression-piston H immediately lowered. The valve H' is caused to open by coming in contact with the projection on the 30 rod N and is raised, permitting the explosive material below the piston H to escape into the space above, the rod N being lowered by the movement of the piston H, which lowering is permitted by the spring n³. The compression-piston then commences to move upward while its valve is still held open, and the valve H is only closed after it reaches a point where the spring n³ fails to hold it open and overcome the tendency of the spring H². From that point on the movement of the compression-piston compresses the charge in the 35 space between the extreme outer edge of the piston D and the piston H, and immediately as the impact-shoulder d passes the port leading from the compression-chamber the final movement of the piston H reestablishes the compressed condition of the gas which has been liberated into the chamber between the abutment and the walls of the piston D. At this moment the charge is exploded and 40 the cycle of operation is repeated. The tim-

ing of the movement of the compression-piston is of course to be governed by the shape and proportion of the cams K K'. Should it be necessary to utilize the full or maximum charge of material, it is only necessary to remove the projection n on the rod N, so that it will not effect the movement of the valve H, but the latter will be raised from its position on its seat by the explosive charge trapped below the piston H, and as soon as 45 the piston H commences to move upward the valve will automatically close and trap the entire charge above the compression-piston.

50 The details of the construction of the engine above described are susceptible of wide change, and in actual construction may require modifications. The principle and nature of the invention, however, is fully disclosed, and I do not wish to be limited to the 55 construction shown and described.

55 The special construction of packing which is herein shown and described is not herein claimed, in that the same will be made the subject-matter of a subsequent application.

60 Having thus described the invention, what is claimed as new, and desired to be secured by Letters Patent, is—

1. In an explosive-engine, the combination with a working cylinder having a rotary piston therein and a movable abutment, of a compression-cylinder having a valveless communication with the working cylinder, and a piston in the compression cylinder for compressing the charge against the rotary 65 piston and the abutment.
2. In a gas-engine the combination with a working cylinder and a rotary piston therein, of a compression-cylinder having direct communication with the working cylinder, a reciprocating piston in the compression-cylinder, a valve in the piston, means for reciprocating the compression-piston, and means for regulating the movement of the valve.
3. In a rotary explosive-engine, the combination with a working cylinder, of a compression-cylinder having a compression-piston therein, a spring-actuated valve located in the piston, means actuating the piston, and a governor adapted to engage with the valve to 75 regulate the moving interval of the valve.
4. In a rotary explosive-engine, the combination with a working cylinder, of a compression-cylinder having a piston therein, means for actuating said piston, a spring-pressed valve within the piston having a stem projecting beyond the compression-cylinder, and an adjustable governor adapted to engage the stem to vary the action of the valve.
5. In a rotary gas-engine the combination with a working cylinder, of a compression-cylinder having a compression-piston therein, means for actuating the piston, a valve in the piston, and an explosion-chamber in the forward end of the compression-cylinder, the 85

two cylinders and the explosion-chamber being always in free and unobstructed communication.

6. In a rotary explosive-engine, the combination with a working cylinder, of a compression-cylinder, a compression-piston working in the compression-cylinder, a valve connected with the piston, an explosion-chamber in the end of the compression-cylinder, and the two cylinders and the explosion-chamber being always in free and unobstructed

communication, a cross-head connected with the piston of the compression-cylinder, and cams for actuating the cross-head to move the piston.

In testimony whereof I affix my signature in presence of two witnesses.

WILLIAM W. HENDERSON.
